AUTOMOBILE HEATER

William R. Beck and Albert E. Beck, Willimantic,
and Charles Krombie, South Coventry, Conn.

Application January 12, 1933, Serial No. 651,836

1 Claim. (Cl. 137—75)

This invention relates to improvements in automobile heaters of the hot water type, in which water from the engine cooling system of an automobile is circulated through a hot water heater located in the body of the automobile for heating the latter.

The engines of certain automobiles are equipped with cooling systems of the thermo-siphon type in which the difference in the temperature of the water within the radiator and the water jacket of the engine is solely relied upon for causing circulation of the water from the radiator, through the water jacket of the engine and back to the radiator. In this type of cooling system, wherein no pump is used to forcibly and rapidly circulate the water, the circulation is obviously comparatively slow and non-positive, and for this reason it has heretofore been impossible to satisfactorily utilize heaters of the hot water type in automobiles whose engines are equipped with cooling systems of the thermo-siphon type. The warm or hot water would simply flow in the path of least resistance from the water jacket of the engine to the top of the radiator past the branch connection to the water heater, with very little of the warm water occasionally or intermittently passing to and through the water heater in the body of the automobile. Accordingly, the heater would not be constantly heated and would therefore be very inefficient and unsatisfactory in practical operation.

The primary object of the present invention is to provide means for positively diverting the required portion of warm water from the thermo-siphon cooling system of an automobile engine continuously to and through a hot water heater located in the body of the automobile, whereby the use of such hot water heater in connection with the mentioned type of cooling system will be attended with efficient and satisfactory results.

More specifically, the present invention contemplates the provision of a branch connection at a point between the water outlet of the engine water jacket and the inlet of the radiator of a thermo-siphon engine cooling system to facilitate passage of warm water from the cooling system to a hot water heater located in the body of the automobile, which branch connection has an intake end extending into the conduit or passage between the engine water jacket and the radiator, opening in a direction opposed to the direction of flow of the water so as to positively divert the necessary portion of warm water from the cooling system in a continuous manner to and through the water heater, thereby making pos-

sible the efficient and satisfactory operation of hot water heaters in automobiles having engines equipped with cooling systems of the thermo-siphon type.

The invention consists in the novel form, combination and arrangement of parts hereinafter more fully described, shown in the accompanying drawings and claimed.

In the drawings:

Figure 1 is a fragmentary view of an automobile, partly in longitudinal section and partly in side elevation, having a thermo-siphonic engine cooling system equipped with a hot water heater in accordance with the present invention. 10

Figure 2 is an enlarged fragmentary section 15 showing the detailed construction of the branch water connection used in the construction of Figure 1 for diverting the warm water from the engine cooling system to the hot water heater.

Figure 3 is a fragmentary plan view showing 20 the manner in which the water outlet nipple of the engine jacket may be notched to receive the branch water connection as in Figures 1 and 2 so as to effect positioning of the branch connection as near as possible to the top of the water 25 jacket at its outlet, in existing engine cooling systems of the thermo-siphon type.

Figure 4 is a transverse section on line 4—4 of Figure 2; and

Figure 5 is a view similar to Figure 2 illustrating a modified form of the invention wherein the branch outlet may be integrally formed at the water outlet of the engine water jacket during manufacture. 30

Referring more in detail to the drawings, 35 indicates the body of an automobile whose engine 6 is equipped with a water cooling system of the thermo-siphon type, wherein the water jacket 7 of the engine has a top outlet nipple 8 connected with the top inlet 9 of a radiator 10 40 by means of a hose connection 11, and wherein the bottom outlet of radiator 10 is connected to the bottom of the water jacket 7 by a hose connection 12. As is well known, the water circulates in a system of this kind in the direction 45 indicated by the dotted arrows in Figure 1, and the difference in the temperature of the water within radiator 10 and within engine jacket 7 is solely relied upon for causing such circulation of the water, the circulation being necessarily 50 relatively slow and non-positive.

It has heretofore been proposed to heat the interior of the automobile body 5 by means of a water heater 13 of any well known or preferred construction, suitably mounted in an elevated 55

position within the automobile body and having water inlet and outlet connections respectively connected with the supply and return connections 12 and 11 from the bottom of radiator 10 to the 5 jacket 7 and from the top of jacket 7 to the top of radiator 10. However, in heretofore installing such a water heater, the connections 12 and 11 were merely provided with ordinary branch outlets connected by conduits 14 and 15, respectively 10 with the outlet and inlet of water heater 13. Due to the slow and non-positive circulation of water in the engine cooling system of this type, the warm water was found to follow the path of least resistance by flowing from the top of water 15 jacket 7 to radiator 10, with very little of the warm water intermittently passing to and through water heater 13 by way of pipe or conduit 15. Use of the water heater in connection with this type of engine cooling system has accordingly 20 heretofore been found very unsatisfactory.

In accordance with the present invention, a branch water outlet for connection by the conduit 15 with the inlet of water heater 13 is provided in the engine cooling system between the top outlet of jacket 7 and the top inlet 9 of radiator 10, as close to the engine 6 as possible, where the water is the warmest, said branch water outlet 16 having an intake end 17 projecting into the water passage of the cooling system and having an inlet of relatively large area directed toward and opposed to the direction of flow of the water in the cooling system, as at 18. By this means, the required portion of warm water from the engine cooling system is positively and continuously diverted therefrom into and through water heater 13 by way of branch outlet 16 and conduit 15 so that the water heater 13 will operate satisfactorily and give uniform heat. It will of course be understood that the circulation of water for the heater 13 is effected on the thermo-siphon principle, the hot water from the jacket 7 of the engine 6 rising into and through conduit 15 to the top of heater 13, after which the water passes downwardly as it cools from the bottom of the heater 13 and then downwardly through conduit 14 back to the lower circular toy connection 12 of the engine cooling system between the bottom of radiator 10 and engine jacket 7.

In the form of the invention illustrated in Figures 1 to 4 inclusive, the branch outlet 16 is inserted in the hose connection 11 between the top of the jacket 7 and the top of radiator 10, this form of the invention being particularly adapted for application to existing automobiles. As shown, 55 the branch outlet connection 16 in this instance consists of a short straight nipple passing through the hose connection 11 and having an elbow-like fitting threaded upon the inner end thereof to provide the inlet end 17, the opening in the hose 11 being effectively sealed against leakage by clamping the part of the hose surrounding its opening tightly between the adjacent end of the fitting 17 and an arcuate plate 19 on the outside of the hose through which the nipple of the branch connection 16 passes, a lock nut being threaded on said nipple to force the plate 13 in tight engagement with the hose 11, as at 20. The nipple of the branch outlet 16 projects outwardly to receive the adjacent end of the hose or conduit 15 by which 65 the water is conducted from the branch outlet 70 connection to the inlet of water heater 13. As before stated, the elbow-like fitting forming the inlet end 17 of the branch outlet connection 16 is positioned so as to extend into the passage formed 75 by the jacket outlet nipple 18 and hose 11, and so

as to have its inlet end opposed to the direction of flow of the water as indicated by the arrows in Figure 2, whereby the flowing water is caused to be positively diverted in the desired quantity to the water heater 13 by way of connection 16 and conduit 15. The desired amount of water diverted to the water heater is insured due to this arrangement of the intake end portion of the branch outlet connection and due to the fact that its inlet end opening is of relatively large diameter as clearly seen in Figures 2, 4 and 5. Efficient operation of the heater 13 is thus insured despite the fact that the circulation of water in the engine cooling system is rather slow and induced in a non-positive manner because of the absence of any positive water circulating pump in the cooling system. It is preferred to insert the branch outlet connection 16 as near as possible to the point of exit of the water from the top of the water jacket 7, where the water is hottest. For this purpose, the outlet nipple 8 of the water jacket may be slotted inwardly from its outer or free end as at 21 to receive the nipple member of the connection 16 when the adjacent end of hose 7 is slipped over the nipple 8 of the water jacket after the branch outlet connection 16 is applied to the adjacent end portion of hose 11.

As shown in Figure 5, the branch outlet connection 16 may be cast integrally with the engine water jacket 7 and its outlet nipple 8 during manufacture of the engine, so that the owner of an automobile may readily equip his car with a water heater, if desired, or so that the automobile may be most efficiently equipped with a heater during production. In this form of construction, the intake 35 of the connection 16 may be provided extremely close to the point where the warm water passes from the jacket into the nipple 8, thereby insuring most efficient operation of the water heater. By plugging the outlet end of the connection 16, 40 the producer of the automobile may leave the installation of the water heater to the purchaser of the automobile, but the construction will provide, when placed in use, a positive means for diverting the necessary amount of warm water from the engine cooling system to a water heater at a point where the water is hottest, and in a continuous manner so as to insure efficient operation of the water heater. While the branch outlet connection 16 is shown in Figure 5 as provided adjacent 50 the point of connection of nipple 8 with the top of water jacket 7, when cast integral therewith, it will nevertheless be understood that said branch outlet connection may be advantageously, although possibly less efficiently, cast directly integral with the water jacket itself at a slightly different point or location near the top of the water jacket.

From the foregoing description, it will be seen that I have provided a simple and efficient means for positively and continuously diverting a portion of the hot water from the thermo-siphon type of engine cooling system so as to insure efficient operation of a water heater on an automobile whose engine is equipped with such type of cooling system. Minor changes are contemplated without departing from the spirit and scope of the invention as claimed.

What I claim as new is:

In combination with an engine cooling system 70 embodying water circulatory connections including an outlet nipple for the engine jacket and a hose fitted over said nipple, a branch water outlet connection for said hose having an intake end 75 projecting into the hose, said branch water out-

let further having an inlet disposed axially of said hose and opening laterally in a direction directly opposed to the direction of flow of the water in said hose, said branch water outlet connection comprising a nipple passing through said hose, an elbow fitting threaded on the inner end of the latter nipple and forming said intake end, and means including an arcuate clamping plate on

the latter nipple outside the hose for sealing the latter against leakage where said latter nipple passes through said hose, the outlet nipple of the engine water jacket being slotted inwardly from its free end to receive said latter nipple.
